CLAIM

The ornamental design for a combined transmitter and receiver for locating a lost remote control unit, as shown and described.

DESCRIPTION

FIG. 1 is a front elevational view of the combined transmitter and receiver for locating a lost remote control unit showing my new design with the broken line showing for illustrative purposes only and forming no part of the claimed design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.
